UNITED STATES PATENT OFFICE.

JOHN RAPHAEL ROGERS, OF BROOKLYN, NEW YORK, ASSIGNOR TO MERGENTHALER LINOTYPE COMPANY, A CORPORATION OF NEW YORK.

TYPOGRAPHICAL MACHINE.

1,057,455.

Specification of Letters Patent. Patented Apr. 1, 1913.

Application filed October 2, 1911. Serial No. 652,239.

To all whom it may concern:

Be it known that I, JOHN RAPHAEL ROGERS,
a citizen of the United States, and a resident
of Brooklyn, county of Kings, and State of
5 New York, have invented a new and useful
Improvement, in Typographical Machines,
of which the following is a specification.

My invention relates to typographical machines, and more particularly to that class thereof known to the public under the name "linotype," and of the general organization illustrated and described in Letters Patent of the United States to O. Mergenthaler, No. 436,532.

15 In the respects herein illustrated and de-
scribed the invention refers to the distribut-
ing mechanism, and more specifically to that
portion thereof whereby the matrices are in-
dividually separated from a line and de-
20 livered to the distributing screws and rail.
Somewhat similar devices are illustrated in
my previous Letters Patent No. 942,845,
and in the Letters Patent to Converse, No.
942,848, in both of which are shown and de-
25 scribed means for delivering the thinner
matrices to the distributor at short intervals
and thicker matrices thereto at longer in-
tervals.

In the distributing mechanism above referred to, the toothed matrices are lifted successively to, and suspended by their teeth from, a grooved distributor bar along which they are carried by the threads of adjacent screws, the arrangement being such that each matrix disengages from the bar at the proper point and falls between the screws into its appropriate channel in the magazine. As the machines were commonly constructed, a matrix was lifted into engagement with the feed screws at each revolution thereof, or in other words, there was a matrix between each turn of the screw-threads and the next. In consequence of this arrangement, the distance between thick matrices traveling along the distributor bar was very small, and it sometimes happened that the lower end of an advancing matrix overtook and bound against the side of the preceding one, which had fallen from the distributor bar but had not had sufficient time to clear the advancing second matrix. The result of such a contact between the matrices was an interference with the proper distribution, as well as possible injury to the matrices, or to other machine parts.

The object of the invention is to overcome this trouble, by providing between each matrix and the one following it on the distributor bar, a space sufficient to insure the descent of the first matrix so as to avoid contact with the next, substantially in the same manner as is set forth in the Letters Patent to myself and to Converse previously mentioned. I therefore combine with the ordinary devices for sustaining the matrix line, and for lifting the matrices successively from the end of the line to the screws of the distributor, means controlled by the thickness of the matrices, in such a way that thin matrices will be delivered by each action of the lifting devices to the feed screws, so that each turn of the threads will thus receive a matrix, while on the other hand, the thicker matrices will be lifted by every second action of the lifting devices, so that they are received only between alternate turns of the screw-thread. In this manner the thin matrices are fed along the distributor bar at short intervals, while the thicker matrices are carried at longer intervals.

In many respects my devices are similar to those illustrated for the same purpose in the before-mentioned Converse patent, wherein the lifting finger E (see Figures 1, 2 and 3) is formed with a retaining hook 85 e^1 , adapted to engage at intervals with the stationary plate e^2 . It will be noted, however, that the hook and plate in this construction are located in immediate proximity to that portion of the finger E whereby the 90 matrices are individually engaged. This arrangement of the said retaining means, and their propinquity to the operative end of the finger, occasion considerable disadvantages and inconvenience, and are undesirable 95 for various reasons, and it is therefore one of the principal objects of my invention to provide means for effecting substantially the same results, but which are located at a point remote from that at which the matrices are engaged. 100

Another principal feature of my invention is the provision of the lifting finger or device with means which engage the individual matrices at opposite sides thereof 105 during the lifting action. Means to engage the matrix at its front side are already in use, but there is sometimes a tendency for the matrix to disengage itself in the opposite direction, and therefore I apply means 110

adapted to engage the matrix at the rear side also, the matrix being thus held at both sides during its upward movement.

The invention is susceptible of embodiment in various modified or alternative forms, only one of which is illustrated in the accompanying drawings; and, generally speaking, I do not desire to limit myself to any particular form or embodiment thereof, 10 except in so far as such limitations are specified in the claims.

Referring to the drawings: Fig. 1 is a side view of the distributor lift box, having my invention applied thereto, partly in section and partly broken away to show the operative parts more clearly; Figs. 2 and 3 are substantially similar views, showing the parts in different positions; Fig. 4 is a transverse vertical section through the lift box; 20 Fig. 5 is a detached detail view of the lifting finger and deflecting plate on an enlarged scale; and Fig. 6 is a vertical transverse section showing the engagement of the matrix and finger.

Referring to the drawings, the distributing mechanism is provided as usual with the longitudinally grooved distributor bar or rail A and the rotating conveying screws B. The line of toothed matrices X is delivered endwise and horizontally to the lifting means, this being effected by the shifter or transfer device J, which normally acts in the direction of the arrow in Figs. 2 and 3 to press the matrices against the stationary shoulders or abutments K, K.

The lifting device comprises the pivoted frame or lever C and the lifting finger D pivoted thereto at E. The lever C is reciprocated about its pivot by the cam or eccentric B¹ mounted upon the end of one of the screws B and located in position to engage the yielding rod B², connected to the lever C and held in engagement with the cam or eccentric B¹ by the spring B³, all in the usual manner. The reciprocating finger D is shouldered at its upper end to bear beneath and against the front side of the foremost matrix X, in such manner that it lifts the matrix clear of the detaining shoulders K, K, and into engagement with the feed screws B, by which it is moved horizontally onto the distributor bar A, the shoulders K, K, being inclined upwardly to assist in sustaining the matrix during such operation.

So far as described, the parts are or may be constructed and arranged in the ordinary manner, and if no further provisions were made, the finger D would at each upward movement deliver a matrix, regardless of its thickness, between the feed screws, and in such manner that there would be a matrix between each turn of the threads and the next one. However, in order to present the thicker matrices only to alternate turns of

the screw-threads, I provide the following additional features: At the lower end of the finger D, and beyond its pivot E, I form the finger with the lip F; and to the frame, or other stationary part of the machine, I secure a stationary blade or plate H. A spring G is mounted in the frame C and bears upon the finger D, so as normally to press the finger inwardly, and to cause it to engage beneath the foremost matrix, (see Fig. 1). As each matrix is lifted clear of the abutments K, K, it is pushed forward by the line following behind it under the influence of the transfer device J, and in so doing it moves the finger D to the position shown in Fig. 2, against the force of the spring G. If the matrix lifted be a thick one, the finger will be turned so far that when it descends, and before it disengages from the matrix, the lip F will engage the inner side of the blade H, thus holding the finger in an inclined position, and so that it cannot engage beneath the next matrix in the line, as shown in Fig. 3. It thus follows that the next upward stroke of the finger will be an idle one and that it will fail to lift a matrix. During this second upward movement, however, the lip F will be lifted clear of the plate H, and the finger will spring back against the second matrix forming the front end of the line, and on completing its descent will engage thereunder (see Fig. 1), so that at the third elevation of the finger it will again lift a matrix to the feed screws. As the screws have in the meantime made two rotations, it follows that the second matrix will be received between the third and fourth turns of the screws, and consequently delivered to the distributor bar at a substantial distance from the preceding matrix. The foregoing operations will be repeated whenever the thicker matrices are presented to the lifting finger. When thin matrices are presented thereto, that is to say, matrices of a thickness insufficient to carry the lip F beyond the plate H, the finger will elevate a matrix at each and every stroke. Thus, it will be seen, the matrices are presented to the distributor bar at longer or shorter intervals, according to their thickness, the thickness of the matrices acting directly to control the frequency with which they are delivered, or, in other words, the intervals between them on the distributor bar. As previously indicated, this operation and the results thereof are similar to those set forth in the said Converse patent, but by reason of my improved arrangement the means for momentarily rendering the matrix lifting device inoperative are located at a point remote from that at which the matrices are engaged thereby, thus correcting any disadvantage or inconvenience that otherwise might arise.

The lifting finger D is formed as usual with the shoulder L to engage the bottom of the matrix and the projecting portion or ledge M to bear against the front side thereof during its elevation, and these means are adequate to prevent the disengagement of the matrix therefrom in a forward direction. However, when such a shoulder is employed alone, it sometimes happens that the matrix may be disengaged from the lifting finger in a rearward direction, as for instance when the transfer device J is retracted for the purpose of introducing a new lot of matrices to the distributing box. In order to insure against this contingency, I provide the lifting finger D with means to engage the rear side of the matrix also. Referring more particularly to Figs. 4, 5 and 6, this device is shown in the form of a lip O connected to the rear side of the finger D and adapted to engage the rear side of the matrix X. In my preferred embodiment this lip O is formed with an inclined surface adapted to engage the correspondingly inclined recesses Y formed in the matrices X, as best shown in Fig. 6. It will be seen that during the lifting operation the matrix X rests upon the shoulder L of the finger D, and that laterally it is held at both sides thereof, at the front by the ledge M, and at the rear by the lip O, thereby preventing its disengagement from the lifting finger during the upward movement.

Having thus described my invention, its construction and mode of operation, what I claim and desire to secure by Letters Patent of the United States, is as follows:

1. In a mechanism of the type described, the combination of a pivoted matrix lifting device and means for momentarily rendering the device inoperative, the said means being located at a point remote from that at which the matrices are engaged and at the opposite side of the pivot therefrom.

2. In a mechanism of the type described, the combination of a reciprocating member, and a finger pivoted thereto and formed at one end to engage the matrices and at the other end with means to render it momentarily inoperative.

3. In a mechanism of the type described, the combination of a reciprocating member, and a finger pivoted thereto and formed at one end to engage the matrices and at the other end with means to render it momentarily inoperative, with a stationary device to cooperate with the last mentioned means.

4. In a mechanism of the type described, the combination of a reciprocating member,

a finger pivoted thereto and formed at one end to engage the matrices and at the other end with means to render it momentarily inoperative, and a spring normally tending to hold the finger in operative position.

65

5. In a mechanism of the type described, the combination of the reciprocating member C, and the finger D pivoted thereto at E, the said finger being formed at one end to engage the matrices and at the other end and beyond the pivot with the lip F.

70

6. In a mechanism of the type described, the combination of the reciprocating member C, the finger D pivoted thereto at E, the said finger being formed at one end to engage the matrices and at the other end and beyond the pivot with the lip F, the spring G connected to the said finger and reciprocating member, and the blade H to engage the lip F.

75

7. In a typographical machine comprising distributing apparatus, the matrix separating mechanism, including a shifting device to engage and move the matrices individually, the said shifting device being provided with means to engage the matrix at opposite sides thereof, in order to prevent its lateral displacement from the shifting device.

85

8. In a typographical machine comprising distributing apparatus, the matrix separating mechanism, including a shifting device to engage and move the matrices individually, the said shifting device being provided with means to engage the matrix at the rear side thereof, in order to prevent its rearward displacement from the shifting device.

95

9. The matrix separating mechanism, including the elevating device D formed with the shoulder L to engage and lift the individual matrices, and provided with the lip O to engage the matrix at its rear side, in order to prevent its rearward displacement from the shoulder L.

105

10. In a machine of the class described, the combination with the matrix X formed with the inclined recess Y, of the elevating device D to engage and lift the matrix, and provided with the inclined lip O to engage the inclined recess Y, in order to prevent the displacement of the matrix from the device.

110

In testimony whereof I hereunto set my hand this twenty seventh day of September, 1911, in the presence of two attesting witnesses.
